REPLACEMENT POINT FOR REBUILDING
DRAGLINE BUCKET TEETH

Leroy M. Moore, Folsom, Calif.

Application June 21, 1941, Serial No. 399,077

2 Claims. (Cl. 37—142)

This invention relates to an improvement in rebuilding worn excavator teeth such as are used on dragline buckets, crowd shovels, or on any earth working equipment using teeth.

While it has previously been suggested that, excavator teeth be repointed by welding a new point onto the worn end, I have observed that this practice is not particularly satisfactory for several reasons. For example, the excavator teeth wear away not only on the points but on the face advanced in the cutting of the earth. If such a worn tooth be repointed, it will not present the same cross-section and cutting contour to the earth as it did originally. Consequently, as a cutting tool, it will not be as effective nor as strong.

In accordance with the present invention the worn tooth is not only repointed but is reshaped as well, so that the cutting edge is provided in the proper relation to the cutting face, which face is also reshaped and reformed. This is achieved by a very simple operation.

It is in general the broad object of this invention to provide a novel and improved structure for repointing and refacing a worn earth cutting tooth.

A preferred means for practice of the present invention is shown in the accompanying drawing in which Figure 1 is a bottom view of the renewal tooth.

Figure 2 is a cross section taken along the line 2—2 of Figure 1, while Figure 3 is a side elevation of the renewal tooth.

Referring to the drawing, I have indicated a worn dragline bucket tooth or other excavator tooth at 4. The forward or point portion of this tooth wears away, usually leaving a transversely rounded curved outer edge indicated at 5. The forward or cutting face 6 of the tooth also wears away generally along a line as indicated at 7. With a tooth in this condition, it is necessary that it either be reconstructed or discarded. In accordance with this invention, I provide for repointing and refacing of the tooth by welding a suitable renewal tooth to the worn tooth.

As appears in Figure 2 I have shown associated with the worn tooth 4 a renewal tooth 8

having a certain presently described configuration and made of a suitable metal. At its forward end, the renewal tooth has a cutting face 9 from which tooth faces 11 and 12 taper rearwardly and outwardly to provide a thickened mid-section. Face 12 is continued by a substantially flat front cutting face 14.

As appears in Figure 1, rear face 11, which slopes outwardly toward each side of the renewal tooth, terminates abruptly to provide transversely curved wall 16 sloping down to rearward by tapering portion 17. The radius of curvature of the wall 16 is such that the wall fits snugly against the outer rounded worn end portion of tooth 4.

The width of portion 17 is usually less than the width of the front portion of the worn tooth. The renewal tooth is joined to the worn tooth by welding along the sides of portion 17 and between the wall 16 and the tooth. While I have shown the renewal tooth fitting snugly against the worn tooth, in practice the two will be separated slightly, particularly along wall 16 and along end 18. These spaces and the edges of portions 17 are filled by welding. For convenience, the letter "W" has been applied to indicate the welding or surfaces to be welded in Figures 1 and 2.

I claim:

30 1. A replacement facing point for a worn ground cutting tooth comprising a metal plate having a cutting face along the forward edge thereof, said plate having a substantially flat face on one side thereof and on the other side tapering rearwardly from said edge to provide a thickened mid-section in said plate, said thickened mid-section terminating abruptly to provide an arcuate wall extending transversely of said other side of said plate, said other side including a portion tapering rearwardly from the base of said wall, to a thickness materially less than the thickness of said wall.

35 2. A replacement facing point as in claim 1 wherein the sides of said plate are relieved in those portions of the plate lying to the rear of

LEROY M. MOORE.
